UNITED STATES PATENT OFFICE.

EDWIN T. GREENFIELD, OF KIAMESHA, NEW YORK.

TUBING.

No. 840,766.

Specification of Letters Patent.

Patented Jan. 8, 1907.

Application filed October 30, 1905. Serial No. 285,074.

To all whom it may concern:

Be it known that I, EDWIN T. GREENFIELD, of Kiamesha, in the county of Sullivan and State of New York, have invented certain new and useful Improvements in Tubing, of which the following is a specification.

The invention concerns flexible spirally-wound interlocking tubing (preferably metallic) of the character employed as conduit containing an electrical conductor or conductors and as armoring for electric cables, hose, and the like.

One of the objects of the invention is to provide an improved article of this character having maximum strength without, however, sacrificing the desirable feature of flexibility.

A further object is to provide a structure which may be manufactured with greater ease and at higher speed than is now possible.

The invention may be expressed in tubing formed of one or more strips bent into successive spirals having interlocking edges, tubing so constructed having been disclosed in several patents heretofore granted to me—

as, for example, No. 630,503, Figures 1 and 3. The material (usually steel) of which such tubing is constructed is required to be of such thickness as to adapt the same for practical use for the purpose desired. Naturally

as the thickness is increased greater difficulty is experienced in the forming operation and more power and slower speed are required. Under the present invention these objections

are overcome by employing instead of a strip of the full thickness required two strips each of substantially one-half such thickness, these being formed, as the single strip of full thickness is formed, by bending or winding and lying in spiral form parallel with and ad-

acent to each other. I have found that such parallel and adjacent strips can be given the proper lateral curvature and also spirally formed to complete the tube by the use of less power and at greater speed than are required in the production of tubing from a single integral strip of the full thickness necessary.

Within the scope of this invention the tubing may be formed of a single pair of such half-thickness strips or of two pairs of such strips, as will be understood upon reference

to the patent above named. For the purpose of this disclosure I have illustrated the former construction in the drawings, in which Fig. 1 is a side elevation, and Fig. 2 a longitudinal section.

In the production of this tubing, two (preferably metallic) strips *a*', each of approximately one-half the thickness required for the walls of the tube, are laid together, one on the other, and passed simultaneously through a suitable die or dies, whereby they are laterally curved, so that the successive spirals shall interlock while remaining movable relatively to each other to assure flexibility. After being given this lateral curvature the strips are formed into such successive interlocking spirals in any suitable manner—as, for instance, by means of the apparatus described in said patent—the laterally-curving and spirally-forming operations preferably proceeding and the tubing being therefore produced continuously.

Of course the exact lateral curvature forms no part of the present invention. This may vary accordingly, as the tubing is composed of a single pair of parallel and adjacent strips or two pairs thereof. When the latter are employed, one of the pairs will preferably be given a laterally-concave shape, the other overlying the pair first named being given a laterally-convex shape, all as will readily be understood by one skilled in the art.

What I claim is—

1. A tube consisting of a series of spirals formed of a plurality of thicknesses of material of equal width and one directly overlying another, the adjacent edges of said spirals being interlocked, substantially as set forth.

2. A tube consisting of a series of spirals formed of a plurality of thicknesses of material of equal width and one directly overlying another, said thicknesses being similarly curved transversely and said spirals being interlocked at their adjacent edges, substantially as set forth.

This specification signed and witnessed this 26th day of October, 1905.

EDWIN T. GREENFIELD.
